E. C. GLEDHILL

WHEEL FOR ROAD GRADERS

Original Filed Aug. 28, 1923

Inventor

E. C. Gledhill

By

Lacey, Tracy, Attorney

UNITED STATES PATENT OFFICE.

EDWARD C. GLEDHILL, OF GALION, OHIO.

WHEEL FOR ROAD GRADERS.

Original application filed August 28, 1923, Serial No. 659,763. Divided and this application filed March 3, 1925. Serial No. 12,926.

To all whom it may concern:

Be it known that I, EDWARD C. GLEDHILL, a citizen of the United States, residing at Galion, in the county of Crawford and State of Ohio, have invented certain new and useful Improvements in Wheels for Road Graders, of which the following is a specification.

This application is a division of an application, Serial No. 659,763, filed by me August 28, 1923.

The object of the present invention is to provide a wheel for road graders which will be simple in construction, possess great strength, and will not cut into a bank or the wall of a ditch. The invention is illustrated in the accompanying drawing and will be hereinafter fully set forth and defined.

20 The drawing is a transverse section of a wheel embodying the invention.

The axle is provided with a spindle or bearing portion 52 of circular cross section and the hub 53 of the wheel is engaged over the said spindle, anti-friction rollers 54 being preferably fitted between the spindle and the inner circumference of the hub, as will be readily understood. An oil guide or opening 55 may be provided in the hub as is obvious so that lubricant may be supplied to the roller bearings and free rotation of the wheels obtained. A retaining nut 56 is secured to the outer end of the spindle 52 and extends over the outer end of the hub so as to close the same and retain the rollers therein. Adjacent its outer end, the hub is provided with an annular flange 57 having its outer face rabbeted, as shown at 58, and the inner circular edge of a disk 59 seats in the said rabbeted portion, as clearly shown. This disk is a metal plate provided at its outer edge with an annular flange 60 which is rigidly secured to the rim or tread 61 of the wheel and the intermediate portion 62 of the disk or plate is so disposed as to be flush with the outer edge of the rim or tread, as clearly shown. A hub cap 63 is arranged over the retaining nut 56 and has its edge portion turned outwardly to bear against the outer face of the

disk 62 at the inner edge thereof, as shown at 64, while securing bolts 65 are inserted through the hub flange 57, the inner edge portion of the disk and the outer edge portion 64 of the hub cap to secure all the parts together.

When a road grader is at work, the wheels on one side are running in the ditch or gutter side of the road, while the wheels at the opposite side of the machine are running in a higher plane or on the crown of the road. Obviously, a greater strain or weight is imposed upon the lower wheels, and with the usual construction of wheels embodying a plurality of separated spokes, the wheels are forced against the bank of the ditch or gutter so that the edge of the rim or tire cuts into the bank and the spokes exaggerate the cutting away of the bank which is started by the rim or tire. In my present machine, however, by providing a wheel of a disk or closed type and having the greater portion of the disk flush with the outer edge of the tire or tread member of the wheel, I avoid the presentation of relatively narrow or sharp members to the bank of the ditch so that the digging or cutting away of the same is avoided and, instead of such action, the wheel has a troweling effect so that the wall of the ditch is made firm and smooth.

Having thus described the invention, I claim:

In a road grader, the combination of an axle, a hub fitted upon the end of the axle and having an annular flange adjacent its outer end, a retaining cap secured on the outer end of the axle and bearing against the outer end of the hub, a tread member, a disk secured at its outer edge to the said tread member and at its inner edge to the annular flange on the hub, the intermediate portion of said disk being flush with the outer edge of the tread member, and a hub cap enclosing the retaining cap and the end of the hub and having its edge portion secured over the inner edge portion of the disk.

In testimony whereof I affix my signature.

EDWARD C. GLEDHILL. [L. S.] 100
